MANUFACTURE OF MONOMETHYL-PARA-AMINOPHENOL AND ITS SULPHATE

Simon Norman, Providence, R. I., assignor to Industrial Dyestuff Company, East Providence, R. I., a corporation of Rhode Island

No Drawing. Application July 30, 1935,
Serial No. 33,915

12 Claims. (Cl. 260—128)

This invention relates to improvements in the manufacture of N-methyl-para-aminophenol sulphate, and more particularly to improvements in the process of converting para-hydroxy-phenylglycine into N-monomethyl-para-aminophenol, which, in turn, is converted into the sulphate.

It is well known that by heating para-hydroxy-phenylglycine in the presence of a large excess of phenol to about 170° C., decomposition of the glycine occurs with the formation of N-methyl-para-aminophenol. It has recently been proposed to employ an excess of cresylic acid or other protective media, such as xylenols, thymol, carvacrol, and benzaldehyde, in place of phenol, at temperatures ranging from 165° C. to 185° C. The proportions of these media employed are generally from ten to twelve times the weight of the glycine.

It has been extremely difficult to find media which are not required in such large amounts in order to complete the decomposition of the glycine in a reasonable time and which do not resinify when heated for long periods in contact with methylated aminophenol, especially when used in large scale production in the factory. It has also been difficult to prevent decomposition of N-methyl-para-aminophenol formed during the heat treatment. Decomposition of the N-methyl-para-aminophenol and resinification seriously affect the yield of the finished N-methyl-para-aminophenol sulphate, as well as the recovery of the media.

An object of the present invention is, therefore, to provide a process in which the aforesaid difficulties, particularly that of preventing resinification and that of preventing decomposition of the final product, are overcome.

Another object is to provide a highly efficient process in which para-hydroxy-phenylglycine is decomposed under controlled conditions in a medium of such nature as to cause a rupture of the glycine grouping at a relatively low temperature and bring about the completion of the reaction in a relatively short time.

A further object is to provide a relatively inexpensive process by which to carry on the above reaction, and which process permits of practically complete recovery of the final product and of the media in which the reaction is carried out.

The media which are employed in the present process have been found to be even more satisfactory than the products of the hydrogenation of phenols, cresols, and their homologs, and they consist of a whole series of aliphatic ketones.

I have found that any aliphatic ketone, pref-

erably those containing one methyl or ethyl group attached to the C=O linkage and boiling at 145° C. or over, or mixtures of the same, having a resultant boiling range above 145° C., will decompose para-hydroxy-phenylglycine satisfactorily and give the resultant compound, monomethylparaaminophenol.

It has been found that the reactions herein disclosed require much lesser amounts to effect the decomposition than any of the compounds mentioned in the prior art, and still allow a very small amount of by-products and impurities to form.

The following examples serve to illustrate the present invention:

Example 1.—Into a suitable apparatus, charge 30 parts (by weight) of para-hydroxy-phenylglycine and 75 parts (by weight) of methyl-n-amylketone. The mass is now stirred and heated to attain a temperature of about 148° C. The temperature is now maintained at this point for a period of about one hour and the whole stirred until inspection of a sample shows a complete solution has been obtained, following which it can be concluded that decomposition is at an end. The mass in the apparatus is now cooled externally to about 25° C. whereupon it is diluted by the addition of about 100 parts (by weight) of ethyl alcohol and the whole well mixed. The diluted mass is now treated with the stoichiometric amount of concentrated sulphuric acid, which causes the sulphate of N-monomethyl-para-aminophenol to separate from the solution. After stirring the mass for a suitable period of time, it is filtered off and washed with alcohol until the mother liquor has been removed. The N-monomethyl-para-aminophenol sulphate is obtained in excellent yield and high purity. It will be noted that, in this example, 2½ parts of methyl-n-amylketone convert with very satisfactory results 1 part of para-hydroxy-phenylglycine, whereas, in the case of all other solvent media, at least 5 parts and sometimes 10 parts of solvent are required to finish the decomposition in a time short enough, and still allow a very small amount of by-products and impurities to form.

Example 2.—1 part (by weight) of para-hydroxy-phenylglycine is mixed with 5 parts (by weight) of methyl-n-hexylketone, the method outlined in Example 1 being substantially followed. The mass is heated for a period of about 25 minutes, at 160° C.—170° C., and all the glycine is found to be converted. The resulting product

is treated with alcohol and sulphuric acid, as in Example 1.

Example 3.—1 part (by weight) of para-hydroxy-phenylglycine is mixed with 5 parts (by weight) of methyl-n-nonylketone. The mass is heated for about 20 minutes, at 160° C.-180° C., when all the glycine is found to be converted. The resulting product is treated with alcohol and sulphuric acid, as above.

Example 4.—1 part (by weight) of para-hydroxy-phenylglycine is mixed with 5 parts (by weight) of methyl-butylketone and 5 parts (by weight) of methyl-hexylketone. The temperature of the mass is brought to 140° C.-150° C., and conversion occurs in about 20 minutes. The resulting product is then treated as in the previous examples.

Example 5.—1 part (by weight) of para-hydroxy-phenylglycine is mixed with 5 parts (by weight) of methyl-propylketone and 5 parts by weight) of methyl-n-nonylketone. The temperature of the mixture is brought to 150° C.-160° C., and it is converted in about 20 minutes. The process is then finished by treating the mass as above. It will be noted, in this example, that a mixture of a low boiling ketone and a high boiling ketone, to give a boiling range of from 150° C.-160° C., gave a satisfactory result. Consequently, where the boiling point of the pure aliphatic ketone is below 145° C., the addition of enough higher boiling ketone will give a resultant boiling point in the decomposition temperature range, and still give a satisfactory result.

Example 6.—1 part (by weight) of para-hydroxy-phenylglycine is mixed with 5 parts (by weight) of ethyl-undecylketone. The whole is heated to 180° C.-200° C., for a period of 15 minutes, with the resulting formation of monomethyl-para-aminophenol base. The mass is then treated as in the previous examples.

What I claim is:

1. A process of manufacturing monomethyl-para-aminophenol, which process comprises decomposing para-hydroxy-phenylglycine to monomethyl-para-aminophenol in a reaction medium containing essentially a straight chain aliphatic ketone having a boiling point above 145° C.

2. A process of manufacturing monomethyl-para-aminophenol, which process comprises decomposing para-hydroxy-phenylglycine to monomethyl-para-aminophenol in a reaction medium containing essentially methyl-n-amylketone.

3. In the process set forth in claim 2, the steps which consist in mixing 1 part, by weight, of para-hydroxy-phenylglycine with 2½ parts, by weight, of methyl-n-amylketone, heating the mixture for one hour at a temperature of about 148° C., cooling the mass to about 25° C. and diluting it with about 7 parts, by weight, of ethyl alcohol, neutralizing the mass with concentrated sulphuric acid to produce the sulphate of monomethyl-para-aminophenol, and then filtering off and washing the precipitate with alcohol.

4. A process of manufacturing monomethyl-para-aminophenol, which process comprises decomposing para-hydroxy-phenylglycine to mono-

methyl-para-aminophenol in a reaction medium containing essentially methyl-n-hexylketone.

5. In the process set forth in claim 4, the steps which consist in mixing 1 part, by weight, of para-hydroxy-phenylglycine with 5 parts, by weight, of methyl-n-hexylketone, heating the mixture for 25 minutes to a temperature of 160° C.-170° C., treating the resulting product with alcohol and then with concentrated sulphuric acid to produce the sulphate of monomethyl-para-aminophenol.

6. A process of manufacturing monomethyl-para-aminophenol, which comprises decomposing para-hydroxy-phenylglycine to monomethyl-para-aminophenol in a medium containing essentially methyl-n-nonylketone.

7. In the process set forth in claim 6, the steps which consist in mixing 1 part, by weight, of para-hydroxy-phenylglycine with 5 parts, by weight, of methyl-n-nonylketone, heating the mixture to 160° C.-180° C., for a period of about 20 minutes, diluting the resulting mass with alcohol, and adding sufficient sulphuric acid to convert the monomethyl-para-aminophenol base into monomethyl-para-aminophenol sulphate.

8. A process of manufacturing monomethyl-para-aminophenol, which process comprises decomposing para-hydroxy-phenylglycine to monomethyl-para-aminophenol in a reaction medium containing essentially an aliphatic ketone containing one methyl group attached to the C=O linkage and having a boiling point of at least 145° C.

9. A process of the character described, comprising decomposing para-hydroxy-phenylglycine to monomethyl-para-aminophenol in a reaction medium containing essentially a straight chain aliphatic ketone having a boiling point of at least 145° C., and stirring the reaction mixture with a solution containing an amount of sulphuric acid sufficient to convert the monomethyl-para-aminophenol base into monomethyl-para-aminophenol sulphate.

10. A process of the character described, comprising decomposing para-hydroxy-phenylglycine to monomethyl-para-aminophenol in a reaction medium containing essentially a straight chain aliphatic ketone having a boiling point of at least 145° C., diluting the resulting mass with alcohol, and adding sufficient sulphuric acid to convert the monomethyl-para-aminophenol base into monomethyl-para-aminophenol sulphate.

11. In the process set forth in claim 10, the additional steps of stirring the resulting mass for a period of about twenty minutes, filtering off and then washing off with alcohol until the mother liquor has been removed.

12. A process of manufacturing monomethyl-para-aminophenol, which process comprises decomposing para-hydroxy-phenylglycine to monomethyl-para-aminophenol by means of heat in a protecting medium comprising essentially a straight chain aliphatic ketone having a boiling point of at least 145° C.

SIMON NORMAN. 65

CERTIFICATE OF CORRECTION.

Patent No. 2,101,749.

December 7, 1937.

SIMON NORMAN.

It is hereby certified that error appears in the printed specification of the above numbered patent requiring correction as follows: Page 2, first column, line 50-51, claim 2, for "mono-ethyl-para-aminophenol" read mono-methyl-para-aminophenol; and that the said Letters Patent should be read with this correction therein that the same may conform to the record of the case in the Patent Office.

Signed and sealed this 5th day of March, A. D. 1940.

(Seal)

Henry Van Arsdale,
Acting Commissioner of Patents.
